COMBINED SCRAPER AND BRUSH FOR GOLF ACCESSORIES

Lawrence J. Chamberlain, 3243 W. Lawrence Ave.,
Chicago, Ill.

Filed June 15, 1960, Ser. No. 60,980

Term of patent 7 years

(Cl. D9—2)

Fig. 1.

Fig. 2.

Fig. 3.

FIGURE 1 is a perspective view of a combined scraper and brush for golf accessories showing my new design;

I claim:

The ornamental design for a combined scraper and brush for golf accessories, substantially as shown.
